UNITED STATES PATENT OFFICE.

JOHN F. LEWIS, OF SCRANTON, PENNSYLVANIA.

LUBRICATOR.

SPECIFICATION forming part of Letters Patent No. 629,083, dated July 18, 1899.

Application filed December 4, 1897. Serial No. 660,725. (No model.)

To all whom it may concern:

Be it known that I, JOHN F. LEWIS, a citizen of the United States, residing at Scranton, in the county of Lackawanna and State of Pennsylvania, have invented certain new and useful Improvements in Lubricators; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to that class of lubricators which are used in connection with steam engines or boilers and in which the lubricant is displaced by water of condensed steam and fed through a pipe filled with water into a live-steam pipe connecting to the inside of the cylinder and fittings of the steam-engine to be lubricated.

20 The objects of the invention are to provide a device of the kind which will be more uniform in its action and will allow of refilling with lubricant without suspending the action of the device and otherwise rendering greater efficiency.

25 To this end the device consists of the peculiar construction, arrangement, and combination of parts, as herein set forth, and illustrated in the accompanying drawings, in which—

30 Figure 1 is a view in cross-section of the reservoir and main passages of my device. Fig. 2 is a diagrammatic view of one of my lubricators used in connection with a horizontal steam-pipe. Fig. 3 is a view of the same attached to a vertical steam-pipe. Fig. 4 is a horizontal cross-section of a detail of the device, taken on the line *y y* of Fig. 5. Fig. 5 is a vertical cross-section of the same detail, taken on the broken line *x x* of Fig. 4.

35 In the drawings, *A* designates the main reservoir, which contains the lubricant.

40 *B* designates the tripod or stand, the legs of which are attached to the plate *a'*, which is furnished with a bushing tightly fitting it into the bottom of the reservoir, thus holding it solid to the stand. The reservoir is fitted at the top with the plug *C*, closing the opening through the bushing *a*, through which latter

opening the reservoir may be filled with oil or other lubricant. The lower opening *d*, through which the contents of the reservoir 55 may be drained out, is drilled through the plug *D* and is adapted to be opened and closed by the plug-cap *D'*, which is partially unscrewed for the purpose of opening the passage *d* and connecting it with the passages *d'* 60 through the plug-cap. *A'* designates a small supplemental reservoir connecting with the main reservoir by the passage *c'*, the said passage *c'* being controlled by the turn-valve *c*. Into an opening on one side of the said supplemental chamber the bracket *G* is fitted by the threaded shank *g*. This bracket or member *G* is provided in the shank *g* with a lower passage *2'*, which delivers displacement-water, and with an upper passage *3'*, which conveys out the lubricant. It is also provided with turn-valves *H* and *H'* to control the last-named passages, respectively. It is also provided with the turn-valve *K*, designed to control the passage *3'* before the said passage is 75 united with the passage *4'*. Pipes (designated, respectively, *2*, *3*, and *4*) connect from without to the passages *2'*, *3'*, and *4'*. Pipe *4* unites with pipe *2*, which latter-named pipe is a continuation of pipe *1*, having condensation-space above the intersection, and pipe *1* is connected with the live-steam pipe *5*. All the condensation required takes place in pipe 80 *1*, which must be made of sufficient length to furnish the required condensation or may be 85 provided with a condensing-chamber. The pipe *4* is attached below the condensing-space, so as to be supplied with condensation-water from pipe *1* rather than to be used as condensing-space of itself. 90

95 Lubricators have heretofore been constructed in which supplementary circulations corresponding to pipe *4* have been used, but with the condensing-water from an independent source of that which is used to displace the lubricant. By my arrangement of the pipes a good supply of condensing-water is provided, but is kept from rising higher in pipe *1* than the intersection of pipes *2* and *4* by means of the overflow through pipe *4*. This 100 overflow being of warm water continues in my device when the oil-supplying valves are closed, so as to keep the parts warm and ready for operation after a cessation in the use of

the machinery. Pipe 3 is also connected to the live-steam pipe 5 at a point lower and nearer to the engine than the connection of pipe 1. E designates a short glass sight-tube 5 through which the rate of working of the device may be seen.

The operation of my device is more fully described as follows: The reservoir A is filled with oil and closed up tight above and below. 15 The valves C, K, H, and II' are then all opened. Now if the pipe 5 is filled with live steam the water from the condensation which accrues in pipe 1 passes downward through pipe 2 and passages 2', through the chamber A' and passage c', into the main reservoir A, settling on the bottom thereof, thus buoying the lubricant upward, forcing it through the passage c', where it meets the downward-passing water. It fills the chamber A', then forces its 20 way through the passages 3' and through the valve e', and passes upward through the nipple e in the sight-tube E, in which it is joined with the warm circulation from the pipe 4', which enters the sight-tube E' by the space 25 surrounding the nipple e, and the lubricant is thus conveyed by the continuation of passages 3' into the pipe 3 and finally discharged into the live-steam pipe 5. If it is desired to 30 shut off part or all of the flow of lubricant, the valve K is turned accordingly. It is evident that the condensation-water when the valve K is entirely closed off remains at a standstill in pipe 2 below its intersection with pipe 4, for the pipe 4, being left open, conveys away all of the condensation aforesaid 35 and passes it through pipe 3 into pipe 5 in the same manner as when the lubricant-valve K is open. This is of importance for two reasons—first, it keeps the parts warm, as heretofore stated, and, second, it prevents the 40 head or pressure of condensation-water from rising, so as to produce greater pressure when started again than that which existed when the valve K was turned off. I thus secure a 45 uniformity of pressure which has not been attained in lubricators of this class, the condensation provided for in pipe 1 being necessarily sufficient to keep the head in pipe 2 at all times as high as the intersection with pipe 4.

50 When the device is to be refilled with lubricant, the turn-valve c is screwed down, so as to close the passage c. The plug C is then removed and the plug-cap D' loosened, so as to drain all of the water out of the reservoir A, when the reservoir may again be filled from the top with the lubricant to be used. During the process of filling the lubricant which 55 remains in the chamber A' is displaced by the action of the water in pipe 2, thus continuing the flow of lubricant the same as when using the main reservoir. When A is filled, the valve c is of course again unscrewed.

I am aware that in lubricators of this kind a displacement circulation has been supplemented heretofore by a conveying circulation, but they have not been so simplified as to conduct said circulations from the same

source and provide for a continuous overflow for the conveying circulation when the displacement circulation is shut off. In my device the two circulations are conducted from the same level from the same source, and the displacement circulation may be cut off without danger of changing the head or pressure which controls the quantity of oil displaced. 75

Having thus described my invention, what I claim as new, and desire to secure by Letters Patent, is—

1. A lubricator of the kind described having a displacement circulation and a conveying circulation, in combination with a condensing pipe or chamber supplying condensation-water for said circulations from a common point or level whereby equality of pressure is maintained in the said displacement 85 circulation, substantially as described and for the purpose set forth.

2. A lubricator of the kind described using condensation-water for displacing and conveying of lubricant to the point required, and having a main oil receptacle or reservoir into which displacement-water is conducted, in combination with a supplemental chamber or reservoir through which the entrance of said displacement-water and exit of lubricant is made, a substantially vertical passage between the said two reservoirs, a valve by means of which said passage may be closed so as to suspend the passage of condensation-water into the main reservoir during replenishment of the same and the said supplemental reservoir adapted to receive the displacement circulation and continue the flow of lubricant during the said operation of replenishment substantially as specified. 95

3. In a lubricator of the kind described a displacement circulation and a conveying circulation, and a common condensing pipe or chamber adapted to supply both circulations, an oil-chamber adapted to receive the condensation-water of the said displacement circulation as it displaces the oil, and a passage from said chamber adapted to conduct the displaced oil into said conveying circulation, and the head or pressure for said displacement circulation adapted to be maintained at an equality by overflow into the conveying circulation from the common condensing-pipe aforesaid, substantially as specified. 105

4. In a lubricator of the kind described a displacement circulation, a secondary circulation adapted to convey the oil or lubricant and provide an overflow for surplus condensation-water the said secondary circulation and displacement circulation being conducted from a common level in a common condensing chamber or pipe, a condensing-chamber adapted to provide condensation-water for said circulation, a main reservoir and a supplemental reservoir through which supplemental reservoir the displacement circulation aforesaid enters the main reservoir and a valve controlled passage between the said res- 115 120 125 130

ervoirs whereby the said displacement circulation may be shut off from the main reservoir for the purpose of replenishment without suspending the flow of lubricant substantially as described.

5. In a lubricator of the kind described a displacement circulation and a separate conveying circulation, the said circulations originating in a common condenser, a condenser for supplying said circulations, and means for suspending the said displacement circulation by deflecting the surplus condensation-water into the conveying circulation without raising the level or pressure of the head therein, substantially as specified.

6. In a lubricator the combination of a main reservoir and a supplemental reservoir, a passage connecting the same and a valve *c* extending through the supplemental reservoir and adapted to close the said passage, with means for conducting condensation-water into and oil out of the said reservoirs, substantially as specified.

7. In a lubricator the chamber *A* and supplementary chamber *A'* with a passage *c'* con-

necting them, together with means for conducting water into and oil out of said main chamber through the supplemental chamber, and means for closing said passage so as to permit of a similar circulation of oil and water in the supplementary chamber during a refilling of the main chamber, substantially as and for the purpose set forth.

8. In a lubricator the combination of a bracket having passages for condensation-water and lubricant, a supplemental chamber with which said passages communicate, the said supplemental chamber communicating with a main chamber through a passage adapted to be closed without suspending the circulations aforesaid, together with a main chamber or receptacle for lubricant and means for conveying the same to the place where required, substantially as specified.

In testimony whereof I affix my signature in presence of two witnesses.

JOHN F. LEWIS.
